UNITED STATES PATENT OFFICE.

FELIX SHAW HAMEL, OF TAMWORTH, ENGLAND.

LOOM.

SPECIFICATION forming part of Letters Patent No. 783,578, dated February 28, 1905.

Application filed May 29, 1903. Serial No. 159,812.

To all whom it may concern:

Be it known that I, FELIX SHAW HAMEL, a subject of the King of Great Britain and Ireland, and a resident of Tamworth, in the county 5 of Stafford, England, have invented certain new and useful Improvements in Looms Chiefly for Weaving Narrow Fabrics, of which the following is a specification.

This invention has for its object the construction of a loom chiefly for weaving narrow fabrics which shall be capable of being driven or operated at a high speed, and therefore capable of a rapid rate of output, and which shall be simple in construction and comparatively 15 cheap to manufacture.

A further object is to render such loom capable of long and continuous running with little or no attention on the part of the operator, and therefore permit of one operator attending 20 to a larger number of looms than heretofore, also to provide for the automatic stopping of the loom when either the weft or warp fails.

To permit of the invention being more readily understood and carried into practical effect, I have hereunto appended a set of drawings, 25 whereon—

Figure 1 illustrates a side elevation, partly sectional, Fig. 2, a front elevation, and Fig. 30 3 a plan, of a loom constructed in accordance with the invention. Fig. 4 illustrates a rear view of a detached portion of the loom to a larger scale. Figs. 5 to 9 illustrate other details separately.

According to the invention the improved loom is built upon a table 1, carried by and suitably bolted to an under frame or stand 2. Beneath such table are the parts for driving the loom, and such parts consist chiefly of a 35 main driving-shaft 4, an auxiliary driving-shaft 5, and a set of "skew" worm-wheels 6 7. The shaft 5 is supported at one end in a bearing-sleeve 8, pivotally mounted in bracket 9, and at the other end is supported by a sleeve 40 10 and spiral spring 11, mounted between the forks of a bracket 12. Immediately above the said shaft is a further shaft 13, mounted in bearings in the under frame 2 and the bracket 12, and upon such shaft is a boss or

collar 14 with a cam-like projection 15, which 50 upon the shaft 13 being rotated—say by the hand starting-lever 16—presses down upon the sleeve of the shaft and forcing such sleeve downward lowers the skew worm-wheel 7 into gear with the worm-wheel 6, and thus 55 causes the shaft 5 to be rotated. For keeping the wheels permanently in gear the shaft 13 has a lever or finger-piece 13^x, which on the shaft 13 being rotated to lower the shaft 5 moves past and becomes retained by the 60 spring-pressed latch-bolt 16^x, carried in the bracket 16^{xx}.

Above the table 2 is the loom proper, the frame of which comprises a pair of uprights 17 18, joined by cross-stays 19, the upright 17 65 being forked at its upper part and forming the support and guides for a set of healds 20 21. These healds, which move up and down alternately with each other in forming the warp-shed, lie as close together as possible 70 and each consists, preferably, of two vertical rods joined by cross-bars top and bottom with wires 23 or other suitable means to support the heald-wires and hold them close together. The means for alternately raising and lowering 75 the healds consist of two disk (or cam) wheels 25 26, mounted upon a cross-shaft 27, and two links 28 29, these latter being connected, respectively, to one of the wheels and one of the healds and the point of connection with the wheels of one link being diametrically opposite that of the other, so that as the wheels 80 rotate one heald moves up (or down) and the other moves down (or up). For imparting motion to the disk-wheels their axis is fitted 85 with a worm-wheel 30 below, and gearing with which is a further worm-wheel 31, mounted upon a shaft 32, carried, by preference, in ball-bearings in the loom-frame. Upon such shaft 32 and upon the shaft 5 are grooved pulleys 90 34 35, and around such pulleys is a driving band or cord 36, by which when rotated the shaft 5 rotates the shaft 27 and disk-wheels 25 26, and thus brings about the motion of the healds. As a modification the band 36 may 95 have a half-twist and pass direct to and around a grooved pulley on the spindle 27.

Upon the front of the upright 17 is secured

a bracket-like part 37, (see Fig. 4,) and such part comprises the weft-spool carrier 38 and the necessary means for supporting and traversing the carrier rapidly backward and forward through the warp-shed, also the take-up motion for the fabric as it is woven and an arrangement of guide-wires for the loom-batten. The weft-spool carrier is, by preference, made of hard wood or hide and is supported on rods 39^a or 39^b, according to whichever side of the loom it is on for the time being, the two sets of rods being in direct alinement with each other and the ends of the rods being rounded and as near together as the weaving operations will allow. For driving the carrier and spool through the warp-shed advantage is taken of the disk-wheels 25 26, upon the inner and opposite faces of which are formed cam projections 40^a 40^b, and between which and mounted in bearings on the upright 17 is a sliding rod 41, the length of the rod being such as to be equal to the distance between the inner face of either disk and one of the cam projections. (See Fig. 2.) The cams are placed at right angles to each other. Hence as the disk-wheels rotate they serve to move the rod 41 first in one direction and then in the other.

Through the medium of a depending plate 42, secured to rod 41, and pin 43 and a slotted lever 44, mounted on a pivot or stud 45, and with which said pin engages, the motion of the rod is utilized, as hereinafter explained, for operating the weft-spool carrier 38. Upon the rear face of the bracket-like part 37 (see Fig. 4) is plate part 46, (see Fig. 9,) in the upper edge of which are two recesses 47^a 47^b. Above and resting upon such plate part is a slide-bar 48, (see Fig. 5,) in the lower edge of which are two recesses 49^a 49^b. Immediately alongside such slide-bar is a fixed rod 50, and upon such a rod is sleeve 51. Engaging a pin 52 on such sleeve is the slotted and free end of the lever 44. Between the said sleeve and the slide-bar 48, also carried by the said sleeve, is a tappet-plate 53. Such plate lies between two slotted picker-plates 54^a 54^b, carried by studs 55, attached to sliding bosses on two fixed rods 56 57. Upon each picker-plate is a pin and bowl 58, (see Fig. 7,) and the relationship of the parts is such that the bowl of one picker-plate is either in one of the recesses in the plate part 46 or on the top edge of such part and in one of the recesses in the slide-bar 48, or one is about to leave and the other about to enter the recesses 47^a 47^b. (See Fig. 9.) In entering and leaving the recesses 47^a 47^b the picker-plate bowls serve to alternately raise and lower the picker-plates, while the motion of the lever 44 serves to drive the sleeve 51, tappet-plate 53, and (through the slide-bar 48 and its recesses) the picker-plates to and fro. In the under face of the weft-spool carrier are two holes or cavities, the position of which relatively to the traverse of the picker-plates 54^a 54^b is such that

as either picker-plate rises it enters one of the holes in the carrier and moving forward or backward imparts the necessary traverse to the carrier, the other picker at the same moment being lowered and retiring from its engagement with the carrier, and so on continuously, one plate taking up the motion and then the other, and thus impelling the carrier through the warp-shed. To assist in raising the picker-plates, their lower ends may be beveled and come against fixed inclines 59, while to prevent them rising too high the bowls may be caused to extend under the overhanging edge of a plate 60, (see Fig. 6,) situated behind the slide-bar 48.

61 is the batten for beating up the weft and composed of thin plates, secured at one end between a set of clamping-plates 62 and at the other end terminating in a bar or rod common to all, the width of the upper end being by preference greater than the width of the lower end. This batten is suspended axially from a pair of arms 63, secured to the upper portions of the upright 17. The necessary swing or beating-up motion is imparted to the batten from the healds through a lever 64, an adjustable connecting-rod 65, a lever 66, fulcrumed on bracket 67, and a pair of links 68^a 68^b, secured, respectively, to the healds 20 and 21, as shown in Fig. 1. As the healds move up and down the batten moves to and fro and beats up the weft, the movements synchronizing with those of the healds in forming the shed and those of the carrier 38. To steady the lower end of the batten and keep it to its work, I provide a series of guide-wires or dents 68, secured to the loom-frame at one end and to a suitable tension-plate 69 at the other end. As a modification I may dispense with guide-wires and use other and suitable means for steadyng the batten.

The warp-threads in passing through the loom pass through the warp-tension devices. (Shown at the left-hand end of Fig. 1.) From thence they pass to the healds 20 21 and then to the taking-up rolls 70 71, duly woven. Intermittent motion is imparted to the roll 70 through link 72, lever 73, and a clutch device 74, this latter being also capable of rotation by hand. This clutch consists of a slotted part 74^a, engaging a flange 74^b on the wheel 74^c and forming part of the lever 73, the sides of the slot in part 74^a being beveled, so that when the lever 73 moves radially it binds on the flange and rotates the wheel. The roll 71 is carried by the lever-arms 71^a and rotates by friction, being firmly pressed by a spring-blade 71^b and spiral spring 75 against the roll 70. A bell-crank lever 76 serves to withdraw and hold the roll 71 from contact with the roll 70, the shorter end of the lever when moved upward pressing against the blade 71^b and by means of its flat end locking the roll in its non-working position.

For stopping the loom in case a warp-thread

What I claim is—

1. In a loom, a set of healds comprising rods and cross-bars, a stationary frame wherein the rods of the healds are guided up and down, a cross-shaft supported by the said frame, and a pair of disk-wheels keyed on such shaft, 45 links so connected to the disks and healds as to impart an up-and-down motion to the healds when the disks are rotated, and means for imparting motion to the disks, a batten pivotally suspended above the warp-threads, and 50 levers and links by which the motion of the healds is imparted to the batten, as set forth.

2. In a loom, a set of healds comprising rods and cross-bars, a stationary frame wherein the rods of the healds are guided up and down, a 55 cross-shaft supported by the said frame, and a pair of disk-wheels keyed on such shaft, links so connected to the disks and healds as to impart an up-and-down motion to the healds when the disks are rotated, and means for imparting motion to the disks, a batten pivotally suspended above the warp-threads and levers and links by which the motion of the healds is imparted to the batten, a bracket-like part secured to the aforesaid frame, a 60 weft-spool carrier, rods for carrying such carrier arranged on opposite sides of the bracket-like part and in line with each other, a pair of picker-plates, and means for causing such plates to alternately rise and move the spool-carrier to and fro, substantially as set forth. 65

In witness whereof I have hereunto set my hand in the presence of two witnesses.

FELIX SHAW HAMEL.

Witnesses:

WILLIAM EASTWOOD,
JOHN CAMP.

breaks I provide each warp-thread with a needle-bar 77, threaded thereon and extending downward through and below a grid-like hanger 78. Below such hanger I arrange a shaft 79, with longitudinal flanges or wings 80, constantly and slowly driven by bevel-wheels 81 and spur-wheels 82 from the loom-shaft 32. The hanger 78 I connect by rod 83 to the upper end of a lever 84, the lower end of which takes into a notch in the head of the spring-pressed latching-bolt 16^x, as shown. When a warp-thread breaks, the needle-bar of such thread drops down into the path of the wings or flanges 80 of the shaft 79, which rotating presses the needle-bar, and with it the hanger 78, sidewise, thereby moving the link-rod 83 and lever 84 and causing the latter to draw the latch-bolt 16^x out of engagement with the finger 13^x of shaft 13, and thus allowing the 20 shaft 5 to rise and stop the loom.

For automatically stopping the loom when the weft fails I employ a rod 85 with finger 86 at its lower end, connected by link 87 to the lever 84, and a finger 88 at its upper end, and this latter I cause to lie in the plane of the weft tension-arm 89. (See Fig. 3.) So long as the weft is intact the tension-arm is clear of the finger 88; but immediately the weft fails such arm moving on its center under the pull of spring 90 comes opposite the finger 88 and meeting it rotates the rod 85, its finger 86 then acting through link 87 upon the lever 84 and stopping the loom.

In conclusion I would observe that it will be obvious that I may readily adapt my invention for weaving wide fabrics and that parts of the invention, such as the improved batten, may with advantage be used in other constructions of looms.
